US00D835390S

(12) United States Design Patent (10) Patent No.: US D835,390 S
Osorio (45) Date of Patent: * Dec. 11, 2018

- (54) SHOE
(71) Applicant: Aquazzura Italia S.R.L., Florence (IT)
(72) Inventor: Edgardo Osorio, Monaco (MC)
(73) Assignee: Aquazzura Italia S.R.L., Florence (IT)
() Term: 15 Years
(21) Appl. No.: 29/578,159
(22) Filed: Sep. 19, 2016

Related U.S. Application Data

- (62) Division of application No. 29/552,716, filed on Jan. 25, 2016, now Pat. No. Des. 776,409.

(57) CLAIM

The ornamental design for a shoe, as shown and described.

DESCRIPTION

FIG. 1 is a front perspective view of a shoe, showing my new design.

FIG. 2 is a right side view thereof;

FIG. 3 is a front view thereof; and,

FIG. 4 is a rear view thereof.

The broken lines showing heels, portions of the upper and portions of the straps in the drawings show parts of the shoe that form no part of the claimed design.

1 Claim, 4 Drawing Sheets
